UNITED STATES PATENT OFFICE.

JOHN E. LEWIS, OF MILWAUKEE, WISCONSIN.

SELECTIVE CHANGE-MAKING MACHINE.

1,392,691.

Specification of Letters Patent.

Patented Oct. 4, 1921.

Application filed November 8, 1915, Serial No. 60,190. Renewed October 29, 1919. Serial No. 334,374.

To all whom it may concern:

Be it known that I, JOHN E. LEWIS, a citizen of the United States, residing at Milwaukee, in the county of Milwaukee and

5 State of Wisconsin, have invented a certain new and useful Improvement in Selective Change-Making Machines, of which the following is a full, clear, concise, and exact description, reference being had to the accompanying drawings, forming a part of

10 this specification.

This invention relates to improvements in selective change making machines.

In all change making machines hereto-

15 fore, so far as I am aware, it has never been possible to vary the amount of change which could be delivered upon operation of the same keys or combinations of keys and this fact has served to materially limit the use

20 of change making machines for some purposes, particularly at moving picture theaters and other places where the value of the tickets or coupons or other commodity sold varies from time to time. For instance,

25 if tickets at one performance are sold at 10 cents each and a customer buys two tickets and hands the ticket seller 50 cents, the change making machine should be designed to automatically eject two tickets and 30

30 cents in change but if the tickets are valued at only 5 cents each and the customer buys two tickets and hands the ticket seller 50 cents, the machine should be capable of automatically ejecting two tickets and 40 cents

35 in change, thus relieving the seller from making mental calculations and minimizing the number of mistakes. However, no such machine has ever been designed, so far as I have been able to determine.

40 The object of my invention is to provide a selective change making machine wherein the amount of change delivered can be varied in accordance with different values of the tickets, coupons or other commodities being dispensed.

Another object of my invention is to provide a change making machine so arranged that the proper amount of change will be delivered with the proper number of tickets or coupons corresponding to the amount received from the purchaser and also corresponding to the value of each coupon or ticket sold.

Another object of the invention is to provide a machine of the character described so arranged that the value of the coupons

or tickets or other commodities dispensed, plus the amount of change delivered, will equal the amount of money received from the purchaser.

60

Another object of the invention is to provide a machine of the character described in the preceding paragraph having adjustable means to change the setting of the mechanism to correspond with different values of the tickets, coupons or other commodities dispensed.

The invention furthermore consists in the improvements in the parts and devices and in the novel combinations of the parts and devices herein shown, described or claimed.

In the drawing forming a part of this specification, Figure 1 is a top plan view of a machine embodying my invention, with the cover thereof removed. Fig. 2 is an elevational view of that end of the machine which is faced by the operator. Fig. 3 is a transverse vertical sectional view taken substantially on the line 3—3 of Fig. 1. Fig. 4 is a longitudinal sectional view taken substantially on the line 4—4 of Fig. 1. Fig. 5 is a broken, longitudinal sectional view taken substantially on the line 5—5 of Fig. 3. Fig. 6 is a transverse vertical sectional view taken substantially on the line 6—6 of Fig. 5. Fig. 7 is a detail sectional view taken substantially on the line 7—7 of Fig. 1. And Fig. 8 is a diagrammatic view illustrating the relative arrangements and locations of the adjustable stops or shoulders, hereinafter described.

In said drawing, 10 designates any suitable form of casing or shell within which the mechanism is mounted, said casing 10 having a front wall 11, side walls 12—12 95 and rear wall 13, the designations front and rear being made with reference to the position of the operator. Near the rear end of the casing is mounted a plurality of coin chutes, the same being designated as 14, 15, 100 16—16 and 17, and corresponding respectively to chutes or holders adapted to receive stacks of 50 cent pieces, 25 cent pieces, 10 cent pieces and 5 cent pieces. Each of said chutes or holders is provided with an offset opening 18 at the bottom thereof over which the lowermost coin of a stack is adapted to be projected and thereby fall therethrough into a chute 19, the latter terminating in a cup 20 at the rear end of 110 the machine from which the purchasers may take the change. The coins are adapted to

feed down the chutes by gravity and be ejected from the bottom of the stacks, one at a time, in a well known manner.

Coöperating with each of the coin chutes 5 is an ejector, the same being referenced 21, 22, 23, 24 and 25, and corresponding respectively with the coin chutes 14, 15, 16, 16 and 17. Each of the ejectors 21 to 25 is connected to and operated by an inverted 10 **U** shaped member, the same being referenced 26, 27, 28, 29 and 30, (see Fig. 4) and corresponding respectively with the ejectors and coin chutes 21 and 14, 22 and 15, 23 and 16, 24 and 16, and 25 and 17. Each of the 15 **U** shaped members extends crosswise of the machine and substantially the entire width thereof, each member 26, 27, 28, 29 and 30 being pivoted at its lower end on a cross bar 31. The members 26 to 30, inclusive, 20 are held normally in vertical position, as clearly indicated in Fig. 4, and are retracted automatically after each actuation by means of suitable springs 32 at the ends of the bars 31, said springs 32 being arranged as clearly 25 indicated in Figs. 1, 3, 4 and 5. The ejectors 21, 22 and 23 are each in the form of long bars pivoted at their front ends to the respective members 26, 27 and 28, and each has its other end provided with a shoulder 30 33, the same, however, being normally below the level of the lowermost coin of its corresponding coin stack and hence in an inoperative position. The other ejectors 24 and 25 are in the form of bellcranks, as 35 clearly indicated in Fig. 5, the same being pivoted to their respective members 29 and 30 and having their upper arms notched at the outer ends and positioned normally in an inoperative position, as above described 40 for the ejectors 21, 22 and 23. Each of the bellcranks 24 and 25 is provided with a depending arm 34 and 35, respectively, for a purpose hereinafter described.

Also extending transversely of the machine, and adjacent the free ends of the ejectors 21 to 25, is a rod or bar 135 having its ends suitably fixed in the side walls 12—12 of the casing. Pivotally mounted on said bar or rod are three depending bails 36, 37 50 and 38. Also pivotally mounted on the rod 135 is a series of depending arms 121, 122, 123, 124 and 125, said arms 121 to 125 corresponding respectively to the ejectors 21 to 25 and being each located directly beneath 55 its corresponding ejector. Associated with each depending finger or arm and its corresponding ejector is a spring member having an upper arm 39 which engages the underside of its corresponding ejector and 60 a lower arm 40 which is engaged by the depending arm. The bail 36 is extended sufficiently so as to engage all of said depending arms 121 to 125; the bail 37 engages the depending arms 122 to 125; and the bail 38 65 engages the depending arms 123 to 125.

From the foregoing, it will be seen that an oscillation of the bail 38 to the right as viewed in Fig. 5 will actuate the arms 123, 124 and 125, and thereby elevate the ejectors 23, 24 and 25 into operative position. 70 A similar oscillation of the bail 37 will elevate the same ejectors, and in addition the ejector 22 into operative position, and a similar oscillation of the bail 36 will elevate all of the ejectors into operative 75 position. To prevent ejecting an improper amount of change should one of the coin chutes be empty, any suitable means may be provided for preventing the elevation of the ejectors into operative position, and for 80 this purpose I have indicated conventionally a pivoted detent 41 which is normally held in an inoperative position by the weight of the coins in the chute but, when the coin chute is empty, said detent or latch 85 41 is projected into the path of its corresponding ejector and thereby prevents the latter from being elevated to an operative position. Any other suitable means might be employed for this purpose, as will be 90 understood by those skilled in the art.

For determining which of the ejectors 21 to 25 are moved to operative position whenever 25 cents, 50 cents or a dollar is received from the purchaser, I have provided push keys 42, 43 and 44 corresponding to said amounts, respectively, as indicated in Fig. 2. The key 42 is connected by a rod 45 with the bail 38, as shown in Figs. 5 and 6, the 50 cent key, referenced 43, is similarly connected by a rod 46 with the bail 37; and the dollar key, referenced 44, is similarly connected with the bail 36. Hence, when the operator pushes in the dollar key all of the ejectors 21 to 25 will 100 be elevated, the ejectors 22 to 25 when the 50 cent key is pushed in, and the ejectors 23 to 25 when the 25 cent key is pushed in. Said keys 42, 43 and 44 may be returned to normal position after each actuation by any 110 suitable means such as return springs.

The ejectors 24 and 25 may be individually operated by keys 47 and 48, respectively, the 5 cent key 47 being connected by a push rod 49 with the arm 35 of the ejector 25 and the 10 cent key 48 being similarly connected by a push rod 50 with the arm 34 of the ejector 24. Each rod 49 and 50 at its inner end is provided with an elongated slot 51 within which the corresponding arms 34 and 35 of the ejectors are mounted so that there is a certain amount of lost motion of the arms 34 and 35 permitted. (See Fig. 5.) This is done in order to permit the elevation of the ejectors 24 and 25 into operative position by means of the bails 36, 37 and 38, as heretofore described. The rods 49 and 50 at their inner ends are suitably supported on the arms 34 and 35 by means of transverse pins 52—52, as will be apparent. The 130

members 29 and 30 to which the ejectors 24 and 25 are pivoted respectively will be returned to normal by their corresponding springs 32, which will also return the rods 5 49 and 50 with their respective keys 47 and 48 to normal position, and in order to overcome the tendency of the ejectors 24 and 25 to remain in an operative position, due to any frictional resistance afforded by the 10 rods 49 and 50 while the latter are being returned to normal, I provide springs 53 suitably connecting the upper, substantially horizontal arms of the ejectors 24 and 25 with their respective members 29 and 30, as 15 clearly shown in Fig. 5. The 5 and 10 cent keys are employed to directly eject 5 or 10 cents in change whereas the 25 cent, 50 cent and dollar keys are employed when those are the respective amounts given by the 20 purchaser to the operator or seller and the proper change is to be made, as hereinafter described.

It is desirable in selling the tickets or coupons to automatically eject the proper 25 number of coupons or tickets desired by the purchaser and for this purpose any suitable or well known mechanism may be provided, one form of which I have indicated conventionally at A in Fig. 1. This ticket or coupon 30 ejecting device may be operated to deliver 1, 2, 3, 4 or 5 tickets at a time by means of the push buttons or keys 54, 55, 56, 57 and 58, respectively. But I do not deem it necessary to illustrate or describe in detail connection 35 from said push buttons or keys to the ticket feeding or cutting means A, inasmuch as such specific connection *per se* does not form a part of my invention. Each of the 40 keys 54 to 58 is preferably mounted on a shank 59 which is slidably but non-rotatably mounted in the front wall 11 of the main frame or casing. Each of the shanks 59, as 45 shown most clearly in Fig. 7, is provided with a longitudinal bore within which is rotatably mounted the reduced end 60 of a push rod. There are five push rods, 61, 62, 63, 64 and 65, corresponding respectively to the keys or buttons for the units 1, 2, 3, 4 and 5. Each push rod 61, etc., is rotatably 50 and slidably mounted at the end adjacent the front wall 11 of the machine in a fixed partition 66 of the machine, and the opposite ends of said push rods are similarly suitably mounted in fixed brackets 67 near the coin 55 chutes. (See Figs. 1 and 4.) Each push rod 61 to 65 carries a plurality of spider-like members S, the push rods 61, 62, 63 and 64 each carrying five of said members and the push rod 65 carrying two of said members, 60 said members S being arranged and located relatively to the pivoted members 26, 27, 28, 29 and 30, as best illustrated in Figs. 1 and 4. Each of the members S is provided with one or more projecting shoulders or lugs 69, 65 some of said members S having one shoulder

or lug, some two, some three, and others four, the arrangement and spacing of said lugs 69 being as diagrammatically illustrated in Fig. 8. Each member S is rigidly attached to its corresponding push rod and 70 therefore rotatable when the push rod is rotated, for the purpose hereinafter described. On each of the push rods 61 to 65 on the front side of the partition 66 is splined a gear 70, said gears 70 being prevented 75 from displacement by means of a depending rib 71 secured to the top wall or cover 72 of the casing. The push rods 61 to 65 are slideable relatively to the gears 70 but being splined therewith rotate when the 80 gears are rotated. The series of gears 70, as indicated by dotted lines in Fig. 2, and in full lines in Fig. 1, are meshed with each other. The one on the push rod 61, is also meshed with another gear 73 suitably rotatably supported on the partition 66, and the gear 73 has also meshed therewith another gear 74 suitably rotatably mounted on the partition 66. The stud or shaft to which the gear 74 is secured is extended through 90 the front wall 11 of the casing and at its outer end has secured thereto a knob 75 by which it may be turned, and an indicating finger 76. The front wall of the machine may be suitably provided with legends designating 5 cent, 10 cent, 15 cent and 20 cent 95 values, as indicated in Fig. 2. The indicator 76 is shown as set for tickets or coupons of a 5 cent value and the arrangement of the lugs 69 in the diagrammatic view of Fig. 8 are illustrated for the same value.

The operation is as follows: Assuming that tickets or coupons or other commodities of a 5 cent value per unit are being sold, the machine is set with the parts in the position shown in the drawings. If a purchaser 105 wishes to buy one ticket or coupon and hands the operator \$1.00, the operator first pushes the dollar key 44 and then the unit key 54. The operation of the dollar key 44 will 110 actuate the bail 36 and thereby raise all of the ejectors to operative position. Upon subsequent actuation of the push rod 61 from the key 54, the lugs 69 indicated diagrammatically in Fig. 8 in the upper horizontal 115 row and which project downwardly, will engage the pivoted members 26, 27, 28 and 29, thereby ejecting a 50 cent piece, a 25 cent piece, and two 10 cent pieces, making a total of 95 cents. Similarly, if the purchaser 120 hands the operator \$1.00 and desires two 5 cent tickets the operator pushes the dollar key and then the two digits key, referenced 55. Thereupon those depending lugs or shoulders 69 indicated diagrammatically in Fig. 8 in the second horizontal row will engage the members 26, 27, 28 and 30, thus 125 ejecting a 50 cent piece, 25 cent piece, 10 cent piece, and a 5 cent piece making a total of 90 cents, the correct change.

From the preceding, it is believed that the operation for 3, 4, and 5 tickets will be understood. In the event the purchaser hands the operator 50 cents and desires one 5 cent ticket, the operator pushes the 50 cent key, referenced 43, and the unit key, referenced 54. This will cause the actuation of the bail 37 and will raise all of the ejectors except that for the 50 cent stack into operative position. Upon actuation of the unit key 54, the same members 26, 27, 28 and 29 will be actuated as heretofore described but on account of the ejector associated with the 50 cent stack of coins being inoperative, 15 the amount of change delivered will only be a 25 cent piece and two 10 cent pieces, a total of 45 cents, the correct change. Corresponding results will be obtained when 2, 3, 4 or 5 tickets are sold. When the purchaser 20 hands the operator 25 cents, the 25 cent key referenced 42 is pushed, thereby actuating the bail 38 and upon subsequent actuation of any of the unitary keys 54 to 58 the change delivered will be 25 cents less than 25 when the 50 cent key was actuated or 75 cents less than when the dollar key was actuated.

The foregoing describes the operation when a 5 cent ticket or coupon is being 30 sold.

If now, a ticket or coupon of 10 cent value is to be sold, the indicator 76 is turned 90 degrees in a clockwise direction as viewed in Fig. 2, which thereby shifts the train of 35 gears 74, 73 and 70—70 through an angle of 90 degrees and hence, the push rods 61 to 65, as will be seen. The push rod 61 is rotated in a clockwise direction, the push rod 62 in a counter-clockwise direction, the 40 push rod 63 in a clockwise direction, the push rod 64 in a counter-clockwise direction and the push rod 65 in a clockwise direction, these directions being indicated by arrows in Fig. 8, adjacent the left hand vertical column. This will bring all those lugs or 45 shoulders 69 on the push rod 61 which extend horizontally on the right hand side of the rod, as viewed in Fig. 8, to the lowest or operative position. The same will be true 50 of the similarly located lugs or shoulders 69 carried by the rods 63 and 65. In a corresponding manner, the lugs or shoulders 69 carried by the push rods 62 and 64 which 55 extend horizontally to the left, as viewed in Fig. 8, will be brought to a depending vertical position. Hence, if the purchaser hands the operator \$1.00 and buys one 10 cent ticket the operator pushes the dollar key 44 and the unit key 54, whereupon those 60 lugs or shoulders which I have indicated at A—A in Fig. 8 will engage and actuate the members 26, 27, 28 and 30, thus ejecting a 50 cent piece, a 25 cent piece, a 10 cent piece and a 5 cent piece, a total of 90 65 cents, the correct change. Similarly, if

the purchaser buys two tickets and the key 55 is pushed the shoulders or lugs b—b indicated in Fig. 8 will engage and actuate the members 26, 27 and 30, thus ejecting a 50 cent piece, a 25 cent piece and a 5 cent 70 piece, a total of 80 cents, the correct change. Similarly, for three 10 cent tickets the lugs or shoulders c—c shown in Fig. 8 will engage and actuate the members 26, 28 and 29, thus ejecting a 50 cent piece and two 10 cent 75 pieces, a total of 70 cents, the correct change. When 4 or 5 tickets are bought the change will be 60 and 50 cents, respectively, as will be understood. Also, when only 50 cents is handed the operator the amount of change 80 will be 50 cents less than when the dollar key is actuated, and for 25 cents the change will be 75 cents less than when the dollar key is actuated. If now the value of the ticket to be sold is 15 cents, the indicator 85 65 will be turned so as to extend downwardly and point to the 15 cent legend, as shown in Fig. 2. This will bring all of the lugs or shoulders 69 which are shown are extending vertically upwardly in Fig. 8 to 90 a position extending vertically downwardly, and the operation will be as heretofore described. When tickets or coupons of 20 cent value are being sold, the indicator 76 is turned to the 20 cent legend and corre- 95 sponding changes in position of the lugs 69 will occur, as will be understood. If, at any time, the purchaser's correct change amounts to either 5 or 10 cents, I have so designed the machine that this change may 100 be delivered directly.

From the preceding description, it will be seen that I have provided a change making machine so arranged as to take into consideration three variable factors,—the amount 105 of money given the operator by the purchaser, the number of units of the commodity sold or purchased, and the value per unit of the commodity sold. In illustrating and describing my invention, I have used the variable values of the foregoing three factors which would be most commonly encountered in actual practice, but as will be understood by those skilled in the art, the principle of the invention may be embodied in other mechanisms using different values of any one of the foregoing three factors. The number of variations permitted for each factor may be increased or diminished according to the requirements of actual conditions, and many 115 changes and variations may be made in the details of construction and arrangement of parts, as will be readily understood by those skilled in the art, and I contemplate all such changes and modifications as come 120 within the scope of the claims appended hereto.

I claim:

1. In a machine of the character described, the combination with keys denoting the 130

- amounts for which change is to be made, of keys corresponding to the number of units of the commodity being sold, and adjustable means between said keys corresponding to 5 changes in price per unit of said commodity, whereby the amount of change delivered will be correspondingly varied.
2. In a machine of the character described, the combination with a key denoting the 10 monetary amount received, change delivery means, and a coöperating digit key corresponding to the number of units of the commodity sold, of means for varying the relative coöperative action of said keys whereby 15 the amount of change from the amount received will vary inversely as the value per unit of the commodity sold.
3. In a machine of the character described, the combination with a plurality of keys corresponding to different monetary values, 20 coin ejecting means, and a series of keys corresponding to the quantity of the commodity being sold, of means coöperating with said keys and ejecting means adjustable to correspond 25 with different values per unit of the commodity to thereby vary the amount of coins ejected.
4. In a machine of the character described, the combination with keys corresponding to 30 different monetary values, of different denominational digit keys, and value indicating means, all of said keys and means being coöperatively associated to determine the difference in monetary value between any 35 monetary key operated and the product of the digit key operated times the value indicated by said means.
5. In a machine of the character described, the combination with a plurality of keys indicating 40 different monetary values, of a plurality of digital keys, coin ejecting means, and selective variable means interposed between and coöperating with the ejecting means and said sets of keys.
6. In a change making machine, the combination with coin ejecting means, amount tendered keys, and digital keys, the operative relation between the amount tendered 45 keys and the digital keys determining the actuation of said ejecting means, of separate means for varying the relation between the amount tendered keys and the digital keys to thereby vary the amount ejected upon 50 similar operations of the amount tendered and digital keys.
7. In a machine of the character described, the combination with coin holders, coin ejecting means, amount tendered keys, and units of purchase keys, the amount tendered 55 and purchase keys together controlling the operation of said ejecting means, of value per unit purchase designating means, and coöperating means between said value designating means and the purchase keys adapted, 60 upon change of the value per unit purchase, 65 to correspondingly vary the coöperative relation between the amount tendered and purchase keys.
8. In a machine of the character described, the combination with coin holding means, 70 coin ejecting means, amount tendered keys, and purchase keys, the amount tendered and purchase keys together controlling the ejecting means, of additional means for varying the coöperative relation between the amount 75 tendered keys and the purchase keys whereby, upon change in value of the purchase, the same operations of similar purchase and amount tendered keys will correspondingly change the amount delivered by the ejecting 80 means.
9. In a machine of the character described, the combination with coin ejectors, amount tendered keys, means interposed between said keys and the ejectors for selectively positioning the latter, of a series of digital keys, a series of members for actuating the 85 ejectors, and means associated with each of said digital keys arranged for coöperative relation with said members, said means associated with the digital keys being adjustable to different operative relation with respect to said members whereby, upon similar operations of the amount tendered and digital keys, different actuations of the ejecting 90 means may be accomplished.
10. In a change making machine, the combination with coin ejectors, amount tendered keys, means between said keys and the ejectors for selectively positioning the latter, 100 and a series of bails for actuating the ejectors, of a plurality of purchase keys adapted to actuate said bails, said purchase keys being provided with adjustable means for selectively actuating said bails. 105
11. In a change making machine, the combination with coin ejectors, amount tendered keys, and a series of purchase keys, the amount tendered and purchase keys being coöperatively associated to determine 110 the actuation of the ejectors, of purchase value indicating means, and connections between said value indicating means and the purchase keys for adjusting the positions of the latter with respect to the amount tendered keys, to thereby vary the actuations 115 of the ejectors in accordance with the value indicating means.
12. In a change making machine, the combination with coin ejectors, amount tendered 120 keys, means operative from said keys for selectively positioning the ejectors, a series of pivoted bails for actuating the ejectors when positioned, of a series of purchase keys each having adjustable elements for engaging said bails to actuate the latter, a purchase value indicating member, and gearing interposed between said value indicating member and said adjustable members of the purchase keys for varying the operative 125 130

position of the latter in accordance with changes in the purchase value indicating member.

13. In a change making machine, the combination with coin ejectors and amount tendered keys, of purchase keys, and means interposed between said purchase keys and the ejectors for selectively operating the latter, said interposed means including a series of elements for directly actuating the ejectors, and a rotatable rod operated by each of the purchase keys, each of said rods having a series of elements thereon rotatable to different positions for selectively engaging said members.

14. In a change making machine, the combination with coin ejectors and amount tendered keys, of purchase keys, and means interposed between said purchase keys and the ejectors for selectively operating the

latter, said interposed means including a series of elements for directly actuating the ejectors, and a rotatable rod operated by each of the purchase keys, each of said rods having a series of elements thereon rotatable to different positions for selectively engaging said members, a rotatable purchase value indicator, and gearing between said value indicator and said rotatable elements arranged, upon rotation of the value indicator, to indicate different values, to correspondingly change the position of said elements.

In witness that I claim the foregoing I have hereunto subscribed my name this 13 day of Oct. 1915.

JOHN E. LEWIS.
